(57) **CLAIM**

The ornamental design for a handle, as shown and described.

DESCRIPTION

In a preferred embodiment, the nature of this product is as a plumbing handle primarily useful for controlling a valve stem.

FIG. 1 is a top, right, front perspective view of a handle embodying my new design;

FIG. 2 is a right side elevational view thereof, the left side elevational view being a mirror image of the right side shown;

FIG. 3 is a front elevational view thereof;

FIG. 4 is a rear elevational view thereof;

FIG. 5 is a bottom plan view thereof; and,

FIG. 6 is a top plan view thereof.

The broken line representations of a valve body in FIGS. 1-4, of plumbing connections and conduit in FIGS. 2-4, of fasteners in FIGS. 2-5, and of an interior wall in FIG. 6, are for the purpose of illustration only, and form no part of the claimed design.
